UNITED STATES PATENT OFFICE.

MARTIN R. CROSSMAN, OF BOSTON, MASSACHUSETTS.

MATCH-POCKET.

1,167,799.

Specification of Letters Patent. Patented Jan. 11, 1916.

Application filed January 23, 1915. Serial No. 4,052.

To all whom it may concern:

Be it known that I, MARTIN R. CROSSMAN, a citizen of the United States, residing at Boston, county of Suffolk, State of Massachusetts, have invented an Improvement in Match-Pockets, of which the following description, in connection with the accompanying drawing, is a specification, like characters on the drawing representing like parts.

This invention relates to match pockets, such as are adapted to be attached to the clothing, and it has for its object to provide a novel match pocket which can be securely fastened to the vest or any other part of the clothing, which can be worn without inconvenience, and which will securely hold the matches, while at the same time having provision for scratching them, and which 20 has other novel features, all as will be more fully hereinafter described and then pointed out in the appended claims.

In the drawings wherein I have illustrated a selected embodiment of my invention, Figure 1 is a perspective view showing my improved match pocket secured in position on a man's vest; Fig. 2 is a front view of the match pocket; Fig. 3 is a section on the line $x-x$, Fig. 2; Fig. 4 is a section on the line $y-y$, Fig. 2; Fig. 5 is a view of the match-scratching element removed.

My improved match safe comprises a body portion 1 of leather or any other suitable material which is folded over at its lower end, as at 2, to form the match-receiving pocket 3, the edges 4 of the folded-over portion being fastened together by stitching or otherwise. Situated in front of the pocket 3 is a match-scratching member 5 which may be of any suitable material adapted to light either safety, parlor or ordinary sulfur matches. This match-scratching member 5 is preferably of comparatively stiff but resilient material, such, for instance, as sheet metal, and if desired one portion 6 thereof may be provided with a match-scratching composition adapted to ignite the so-called safety match, while another portion 7 thereof may be simply roughened thereby to provide for scratching a sulfur match or a parlor match.

8 designates a cover member which overlies the match-scratching member 5 and is provided with a central opening 9 through which a portion of the match-scratching

member is accessible. This member 8 may be made of any suitable material and it covers the edges of the match-scratching member and gives a more or less ornamental finish to the front of the device.

60

My improved match pocket is adapted to be detachably secured to some part of the clothing, such, for instance, as a gentleman's vest, and I have provided herein means for attaching the match pocket to the clothing, 65

which means also serves for holding the match-scratching member and the finishing cover member 8 in position. The attaching means herein shown are in the form of pins 10 adapted to extend through the match 70

pocket and through the garment to which the device is to be secured, said pins being provided with fixed heads 11 and with removable heads 12. These pins 10 are pref- 75

erably inserted through the device so that the fixed heads 11 appear on the exterior surface thereof, and said pins 10 extend through the protective or finishing cover 8 and through notches 13 formed in the ends 80

of the match-scratching member 5. Both 85 the match-scratching member and the protective cover are preferably curved slightly, as shown. The advantage of this construction is that it enables the device to lie closely against the body and also serves to hold the matches in the pocket. The device

can be readily applied to a person's vest or his coat by simply removing the detachable heads 12 from the pins and then inserting the pins through the vest or other article of 90

clothing, and subsequently applying the removable heads 12 to the pins again. These removable heads are provided with clamping jaws 14 adapted to engage in a groove 95

15 formed in the pin. The jaws are connected to a portion 16 accessible from the end of the head 12 so that by withdrawing this portion 16 slightly the gripping of the jaws is released and the head can be re- 100

I have also illustrated a pin cushion with my match safe, thus making the article an extremely handy one for any gentleman to carry. This pin cushion is shown at 20 and will preferably be situated immediately beneath the pocket 3. The pin cushion can be formed in any suitable way, and it is provided with an attaching tab 21 which extends up between the front 2 and the match-scratching member 5, the upper edge of the 105

110

tab being sewed or otherwise secured to the edge of the front 2. This pin cushion member and its tab can be of some color which harmonizes well with the color of the body 5 1, thus making a very ornamental article.

The construction herein shown is well adapted to permit of advertising matter being placed either on the protective cover 8, or on the pin cushion portion, or on the body 10 portion above the pocket, thus making the device in the nature of an advertising novelty.

I claim:

1. A match pocket comprising a body 15 member having a match-receiving pocket therein, a match-scratching member overlying the body member, a cover member overlying the match-scratching member and provided with a central opening through 20 which the latter is accessible, and means for detachably securing the match pocket to an article of clothing, said means operating to

hold the match-scratching member and cover member in position.

2. A match pocket comprising a body 25 member having a match-receiving pocket therein, a match-scratching member overlying the body member, a cover member overlying the match-scratching member and provided with a central opening through 30 which the latter is accessible, and attaching pins extending through the cover member and body member by which the device is attached to an article of clothing, said pins engaging the match-scratching member and 35 holding the latter in position.

In testimony whereof, I have signed my name to this specification, in the presence of two subscribing witnesses.

MARTIN R. CROSSMAN.
